UNITED STATES PATENT OFFICE.

ROBERT C. N. COOK, OF LEBANON, INDIANA.

BIDET FOR CLOSET SEATS.

Application filed November 25, 1922. Serial No. 603,144.

To all whom it may concern:

Be it known that I, ROBERT C. N. COOK, a citizen of the United States, and a resident of Lebanon, county of Boone, and State of Indiana, have invented a certain new and useful Bidet for Closet Seats; and I do hereby declare that the following is a full, clear, and exact description thereof, reference being had to the accompanying drawings, in which like numerals refer to like parts.

This invention relates to an improvement in the combination of a closet seat and bidet or spray attachment and has for its object to provide a device of the character specified capable of use in the ordinary manner as a seat, and having a bidet or spray fixture in connection therewith connected with a water supply and normally in inoperative position, and concealed by the seat, but being capable of being brought into operative position when desired.

One feature of the invention resides in the construction of the spray nozzle where by it may be caused to slide back under the seat so as to be concealed and out of the way, and may be caused to slide longitudinally and outwardly to operative position by a suitable and accessible handle.

Another feature of the invention resides in the provision of a mixing chamber for mixing hot and cold water, and thereby controlling the temperature of the spray.

The full nature of this invention will be understood from the accompanying drawings and the following description and claims.

In the drawings Fig. 1 is a plan view of the attachment. Fig. 2 is a section taken on the line 2—2 of Fig. 1.

In the drawings there is shown the usual type of seat construction 10 mounted upon the bowl 11, said seat being hingedly mounted at its rear upon the hinge rod 12 in the usual and well known manner by the brackets 13, said rod being supported upon the bowl 11 by supporting fixtures 14 adjacent each end thereof.

Mounted adjacent the under side of the seat 10 there is a spray nozzle 15 having a reduced threaded end 16 upon which the nozzle 17 may be removably secured, said nozzle having a plurality of perforations therein through which the water may be sprayed. The nozzle 15 is slidably mounted within the housing 18 so as to telescope

therein when in inoperative position. The end of the housing 18 is provided with a packing nut 19 containing suitable packing for preventing leakage therethrough, and permitting the sliding movement of the nozzle. The nozzle and housing are tubular in form and are rigidly secured to the hinge rod 12 by a clamping bracket 20 which may be removably secured to said hinge rod. For operating the nozzle 15 and causing the same to slide in and out of operative position within the housing, there is provided an operating rod 21 secured at its outer end adjacent the end of the nozzle 15 and passing through a suitable bearing 22 rigidly secured to the housing 18 adjacent the forward end thereof. Said rod also passes through the second bearing 23 provided in the securing bracket 20 and thereafter extending laterally at right angles, forming the arm 24 which is provided with upwardly extending handle 25. By pushing the handle rearwardly the nozzle is caused to slide back within the housing 18 to inoperative position. In such position the spray will be positioned beneath the seat and out of the way. When it is desired to use said spray the user pulls the handle 25 toward him, causing the nozzle to slide forwardly from under the seat to operative position.

The rear end of the housing 18 is connected by suitable means to the supply pipe 26 which extends adjacent the flush pipe 27 and is rigidly secured thereto by the securing bracket 28. Said pipe 26 is provided with a valve 29 for controlling the water supply to the nozzle, and is connected with the communicating chamber 30 into which the cold and hot water service pipes 31 and 32 extend, said pipes being controlled by the valves 33 and 34 respectively. This arrangement not only permits the user to control the water supply to the spray by means of the valve 29, but also permits the control of the water temperature through the valves 33 and 34 and the mixing chamber 30.

The invention claimed is:

1. In a device of the character described, the combination with a seat and a water supply pipe, of a spraying nozzle positioned adjacent the under side of said seat, and an operating handle located adjacent the side of said seat for sliding said nozzle longitudinally in and out of operative position whereby it will be positioned under said

seat when in inoperative position and will slide forwardly and longitudinally thereover when moved to operative position.

2. In a device of the character described, the combination with a seat, a hinge rod upon which said seat is pivotally mounted, and a water supply pipe, of an attachment therefor comprising a cylindrical receiving chamber communicating with said water supply, said receiving chamber being mounted adjacent the under surface of said seat, a spraying nozzle adapted to reciprocate within said chamber so as to lie beneath said seat when in inoperative position and extend from beneath said seat when in operative position, and a clamping bracket for removably clamping said receiving chamber to said hinge rod.

3. In a device of the character described, the combination with a flush bowl, a supply pipe for flushing said bowl, a seat, a hinge

rod mounted on said bowl upon which said seat is mounted, and a water supply pipe, of an attachment therefor comprising a cylindrical receiving chamber communicating 25 with said water supply pipe, said receiving chamber being mounted adjacent the under surface of said seat and hinge rod, a spraying nozzle adapted to reciprocate within said chamber so as to lie beneath said seat when in inoperative position, and extend from beneath said seat when in operative position, a clamping bracket for removably clamping said receiving chamber to said hinge rod, and a clamping ring adapted to surround said flush pipe and water supply pipe for rigidly clamping the latter to the former.

In witness whereof, I have hereunto affixed my signature.

ROBERT C. N. COOK.
